CLAIM

The ornamental design for a dog training receiver and transmitter set, as shown and described.

DESCRIPTION

FIG. 1 is a front, top, right side perspective view of a receiver, of the dog trainer, shown separately for ease of illustration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom, left side perspective view thereof;

FIG. 9 is a front, top, left side perspective view of a transmitter, of the dog trainer, shown separately for ease of illustration;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a rear, bottom, left side perspective view thereof; and,

FIG. 17 is a perspective view of dog training receiver and transmitter set.

The broken lines throughout the drawing figures depict portions of the dog training receiver and transmitter set that form no part of the claimed design.
